UNITED STATES PATENT OFFICE

JUANITA B. DICKSON, OF LOS ANGELES, CALIFORNIA

BRASSIERE

Application filed April 30, 1930. Serial No. 448,532.

This invention relates to lingerie or women's underwear apparel and particularly to a woman's article of dress which is adapted to configurate the bust into lines of classic beauty.

An object of the invention is the provision of a garment of the above mentioned character, constructed along geometrical principles and which is designed to support, retain and mold the bust into lines of youthful contour.

This brassière conforms to the natural curves of the figure without tension and affords a maximum of support. If the bust be of natural contour, the garment should be worn for preservation; a saggy and heavy bust is lifted and converged into youthful and graceful lines.

Another object of the invention is the security afforded and assurance of safety accorded the mind of the wearer. The bust is so confined that it cannot slip above or below the garment regardless of movement of parts of the body. The natural line of division between the breast is maintained without any tendency to force the busts backward toward the arm pits.

An important feature of the invention is in the design of the low back and sides, which make it inconspicuous for the modern outer wearing apparel of today.

One of the failures of the present low-cut or backless brassières is, that they do not support the bust sufficiently.

My improved construction embodies a border line of support running from the shoulder strap and across the side portion of the garment thus insuring support and being remedial of the foregoing error of construction.

Aside from the foregoing objects and features is the adaptability of the present invention as a universal garment of wear.

The woman who drives, who rides, who swims, the women of the stage, the athletic, or any other woman who yearns for the beautiful in grace, charm and comfort will find the invention adapted to meet her needs and to suit her taste.

In the accompanying drawings I show a preferred embodiment of my invention. I

do not limit myself to the forms disclosed, since various changes and adaptations may be made therein without departing from the essence of the invention as hereinafter claimed and objects and advantages other than those specifically mentioned are included in its scope.

Referring to the drawings:

Fig. 1 is a front elevation of my improved brassière, the shoulders of the wearer being outlined.

Fig. 2 is a back view of my improved invention, the shoulders and sides of the wearer being outlined.

Fig. 3 is a side view of my improved invention, the upper outline of the wearer's body being outlined.

Fig. 4 is an outstretched view showing a cluster of polygonal figures comprising the patterns of which the breast portion of the brassière is constructed.

Fig. 5 is an outstretched view showing the two outstretched polygonal figures comprising the patterns of which the belt or girdle portion is made, and

Fig. 6 is a front elevation of my improved invention showing it in a flat and outstretched position.

My invention is constructed along geometrical principles and comprises a combination of polygonal figures or patterns as shown in Figs. 4 and 5. In detail, in the cluster of patterns shown in Fig. 4, there is a central diamond shaped piece 8 with a V neck notch 9 at the upper point thereof adapted to overlie the medial line of the body. This large central diamond shaped piece 8 extends from the center of one breast to that of the other and therefore stabilizes the entire structure.

To the right and left of said piece 8 are the polygonal parts 10 and 11. Said part 10 is diamond shaped and said part 11 is rhomboidal shaped. There is also shown in Fig. 4 an imaginary line 12 to indicate the central or medial line of the figure shown in Fig. 1 and about which the component parts 10 and 11 are symmetrical and identical.

The part 10 is joined to the adjacent edge 100

of the piece 8 by lines of stitches indicated by the numeral 13 in Fig. 6.

Likewise the part 11 is joined to the adjacent edge of the piece 8 by lines of stitches 5 14 in the same figure.

The remaining lower edges of parts 10, are in turn stitched together by lines of stitches indicated by the numeral 15, to the remaining upper adjacent edges of part 11, also shown 10 in the latter view. Said parts comprising the entire assembly can be cut from material having a minimum waste, since there are no round edges to contend with.

The aforesaid parts and pieces when properly assembled together form a substantially pyramidal cone shaped bust retriever, the vertex 16 of which extends outwardly a distance equal to the normal protrusion of the ogival bust portion of the wearer from the 20 natural contour lines of her body proper and have an upper and lateral outline which simulates a laterally extended M.

The union of the parts 8 and 11 at the seam 14 forms two continuous lines leading from 25 their intersection at the center of the central portion of the body to the centers or extended vertices of each bust. Said line connecting with a point 17 which is the extreme low point of the center diamond shaped part 8 with 30 the vertex 16 of the bust retriever as aforesaid. The two sections 11 together with the central section 8 may be regarded as forming a portion of the belt, the belt sections 23 forming the remainder thereof.

The upper portions of the cone bust retriever constructed from the pieces 10 are reinforced by a perpendicular line of stitching 18 running from the vertex 16 of the cone to the shoulder strap 20. This feature prevents stretching of the material composing 40 the piece 10 when undue strain is brought to bear on the shoulder strap 20.

The upper portions of the cone shaped bust retriever as seen in Fig. 6, are bordered by 45 strips of material as indicated by numerals 21 and 22. Said strips give added support and adaptability to the brassière. Said straps further cross the belt portion 23 under the arms in a diagonal manner as indicated at 50 24 to prevent gapping.

The cone shaped bust retrievers are connected to a belt or girdle 23, the latter forming the lower and inside section of the garment. Just below the bust, the bust retrievers are stitched to the belt to complete 55 the substantially pyramidal base like construction.

The polygonal pattern of the belt or girdle 23 is shown in two pieces of like construction 60 in Fig. 5, the imaginary line 12 shown in Fig. 4 being continued in staggered relation thru Fig. 5 to show its relation with the former Fig. 4.

The pieces 23 are patterned to an angle between the cones and encircles the body to a

point lower in the back than in the front, a conception of the condition as just outlined may be had by referring to Fig. 3.

It will be observed in Fig. 5 that the ends 25 are cut slantingly, said ends being joined at the center of the garment by lines of stitching as indicated by 26 in Fig. 6 to produce the former result.

The angularly recessed portion formed by lines 27 and 28 of the belt 23 appearing in Fig. 5 take the position of the dotted lines 27' and 28' shown in Fig. 6. Said portions being stitched by lines of stitching coincident with lines 27' and 28', whereby to contour a form fitting sector for the lower ogival base portion of the bust supported from that juncture.

Therefore it will be observed that the lower portion of the cone base when viewed in elevation has a reinforcement edge as well as the upper portion thereof.

The slantingly cut ends 25 when joined together as specified at 26 causes the belt or girdle 23 to take a downward slope from front to rear as indicated by the lines 29 running from the point 17 to the point 30 in Fig. 6 and while conforming to the curve of the body will assume a contour line as indicated by the same numeral in Fig. 3.

There is provided in the central diamond shaped piece 8 a plurality of horizontal tucks 31 and 32 of slightly different lengths. Said tucks being adapted to flatten the material between the busts and at the same time give added fullness at the rise thereof.

The ends of the borders 21 running from the straps 20 to the center 33 of the V of the central diamond shaped piece 8 are fashioned into a small diamond 39 and stitched over the tucks 31 and 32. This construction stays the material between the busts.

The straps 20 are fastened in front at the apices of the upper angle of the pyramidal cone shaped bust retrievers, and in the back they cross the belt diagonally on the inside at a point 34 thus reinforcing the belt material 23 at a point where the most wear comes.

The garment is fastened in the back by loops 35 which overlie the buttons 36. Elastic ribbons 37 join the two sections of the belt thru the medium of the fastenings 35 and 36 just described, the number of ribbons and loops depending on the size of the brassière.

The present day brassières have belts of uniform widths regardless of size of the supporting section of the garment. This greatly detracts from the support of the larger sizes.

When contrasting the view shown in Fig. 6 with that shown in Fig. 1 it will be observed that the vertex 16 of the pyramidal cone shaped bust retriever shown in Fig. 6 is slightly lower than that shown in Fig. 1, and also the reinforcing stitching 18 in Fig. 6 is somewhat longer than the same stitching shown in Fig. 1.

Therefore it will be obvious that when the

brassière shown in Fig. 6 is applied to the figure 38 as shown in Fig. 1, that the bust is not only supported but is fashioned or moulded in shape on account of the position of the vertex 5 being a higher point than that shown in Fig. 6.

It will further be observed when analyzing the two views shown in Figs. 1 and 6, that there is a peculiar adaptability of the 10 brassière to the figure 38 as illustrated in Fig. 1 when compared with the separate showing thereof in Fig. 6.

Each shoulder strap 20 extends along the line of the resultant of the forces applied 15 thereto by the busts which it sustains. The sustaining power of each of said straps 20 is safely anchored to the parts therebeneath by reason of the additional strength afforded by the stitching 18 which aligns with said 20 shoulder straps.

Therefore it will further be obvious that since the reinforcing stitching coincides with the resultant force, the strap 20 will aid in supporting that portion of the breast adja- 25 cent the lower sector of the pyramidal cone shaped bust retriever terminating along the lines of stitchings 27' and 28' thru the medium of said reinforcing stitching.

As a result, the device adapts itself to the 30 torsional movement of the body as when swimming or playing tennis. When an up and down movement of the bust is caused by riding, it will be manifest how the distribution of the forces resulting from the movement of the muscles while indulging in these 35 various exercises are conveyed and resolved along the lines of stitches to accomplish the object of the invention as previously set forth.

Claims:

40 1. In a brassière a pair of breast receiving elements composed of sheet material and having forwardly projecting or swelled forms to fit over the busts, a front belt section extending along the lower edges and having an up- 45 per edge portion overlapping upon the lower portions of said breast receiving elements and stitched thereto while its lower edge portion is spaced below said elements, relatively narrow strips extending along the upper edge 50 portions of said breast receiving elements and thence sloping outwardly and downwardly from the center of the device at each side thereof and terminating at the lower edge of the belt, rear belt sections securable to each 55 other to complete the belt, and shoulder straps secured to the upper portions of said strips and to said rear belt sections.

2. A brassière comprising a central dia- 60 mon shaped section arranged to have its longer diagonal horizontal, and provided with a V-shaped notch at its upper corner, a pair of lateral diamond shaped sections hav- 65 ing their lower inner edges of the same ex- tent as the upper edges of the central section and stitched thereto, the upper inner edges

of said lateral sections being alined with the sides of said notch, rhomboidal sections each having its inner side stitched to the respective lower edge of the first section and its upper side stitched to the outer lower edge 70 of one of the pair of diamond shaped sections, and a pair of belt members having proximal ends stitched together and under-lying the lower parts of the central diamond shaped member and the rhomboidal members, 75 said belt members having wide V-shaped notches in their upper edges at their proximal ends, said notched portions of the edges being stitched to the central diamond shaped member and the rhomboidal section. 80

3. A brassière comprising a central dia- mon shaped section arranged to have its longer diagonal horizontal and provided with a V-shaped notch at its upper corner, a pair of lateral diamond shaped sections hav- 85 ing their lower inner edges of the same ex- tent as the upper edges of the central section and stitched thereto, the upper inner edges of said lateral sections being alined with the sides of said notch, rhomboidal sections each 90 having its inner side stitched to the respective lower edge of the first section and its upper side stitched to the outer lower edge of one of the pair of diamond shaped sections, reinforcing strips extending along the outer 95 upper edges of the pair of diamond shaped members and along the outer edges of the rhomboidal members to the bottom edges of the belt members, other reinforcing strips extending along the edges of the first men- 100 tioned notch and the upper inner edges of the pair of diamond shaped members, and shoul-der straps each secured to the belt and to the upper corner of a respective one of the pair of diamond shaped members. 105
